UNITED STATES PATENT OFFICE.

LOUIS ALBERT O'LENA, OF BROOKLYN, NEW YORK.

METHOD OF KNITTING.

Application filed January 24, 1923. Serial No. 614,556.

To all whom it may concern:

Be it known that I, LOUIS ALBERT O'LENA, a citizen of the United States, residing at Brooklyn, in the county of Kings and State of New York, have invented certain new and useful Improvements in Methods of Knitting, of which the following is a specification.

This invention relates to the production of a knitted fabric having improved characteristics particularly as regards a special nap or pile.

In a prior patent of mine, #1,441,110 of January 2nd, 1923, I have disclosed a method and apparatus for producing a knitted pile fabric by operating a cutter in conjunction with the sinker to sever one of the two loops of thread supported by the sinker during the enchainment operation.

The present invention differs from and is in certain respects an improvement over the invention referred to in that, instead of severing the loops to form the pile, the loops need not be wholly separated and the pile may be formed by the ends of strands or fibers projecting at the bends of the loops. These projecting ends are usually produced by tensioning the loops over the sinkers or loop supports sufficiently to break a portion of the fibers, which then, because of the tensioning and stretching of the material, stand out in the nature of a pile.

The accompanying drawing, forming part of this specification, illustrates a sample of the fabric and a method of producing the same, Figure 1 being a perspective fragmentary and diagrammatic view of a piece of the fabric on an enlarged and exaggerated scale; Figures 2 and 3, side views illustrating the action of the needles in drawing the loops down over the sinkers so as to break the fibers of the upper loops; Figure 4, a diagrammatic illustrating successive stages in the operation; and Figures 5 and 6, enlarged fragmentary side and edge views of a loop with its projecting pile.

In Figure 1 the fabric is shown as knitted with loops 7 from the tops of which project the tufts of fibers 8. The loops are continuous and therefore add strength to the fabric while giving the effect of a nap and the tufts projecting from the loops provide the effect of a pile.

Figures 2, 3 and 4 illustrate how these results may be accomplished by knitting with two threads 9, 10, and by using a

special form of sinker 11, having in addition to the usual thread supporting edge 12, an upper auxiliary edge 13 designed to support the upper thread 9 in the form of a loop 14 separated from and spaced above the loop 15 of the thread 10 supported on the lower edge 12.

The needle which draws these threads down over the supporting edges to form the two loops is indicated at 16 and is shown as of the latch type to partly effect and enable the enchainment operations to take place below the sinker as at 17 in Figures 2 and 3. As the particulars of the enchainment constitute no part of the present invention this feature is not illustrated or described in detail, it being sufficient for this disclosure to understand that the enchainment may be effected in any usual or preferred manner when the needles descend to carry the loops down over the supporting edges of the sinkers.

Figure 4 illustrates in successive steps how the needle in its downward movement first takes hold of the upper thread 9 and then after engaging the lower thread 10 carries both down to substantially the same level. In this action the upper thread is carried the greater distance and consequently is placed under greater tension than the lower thread, so much so that the fibers of the upper loop will be stretched beyond their elastic limit and be ruptured or broken. The tension necessary to effect this result may be obtained by regulating the tension on the thread 9 and by spacing the sinkers closer together than has been customary heretofore. This closer spacing of the sinkers also produces a more abrupt bending of the loops over the supporting edges and this facilitates and makes more positive the breaking action of the fibers.

It will be evident that by properly regulating the tension and other controlling effects the extent or proportion of breakage can be governed to obtain different pile effects. At the present time the preferred practice is to break only sufficient of the fibers to provide a good pile and to leave the loops with sufficient tensile strength to reinforce the fabric. In pulling a loop over a supporting edge the fibers at the outside of the bend are subjected to the greatest strain and these appear to be the ones which break first. This, of course, is an advantage in that these outer fibers are free as soon as they

break to stand up and serve as the pile of the fabric.

What I claim is:

1. The method of producing a knitted pile fabric which includes looping the thread of the fabric over supporting means and tensioning the loops sufficiently to break some of the fibers at the bends of the loops and cause the broken ends of the same to stand out as a pile.
2. The method of producing a knitted pile fabric which includes looping a thread of the fabric over a support with sufficient tension to break the fibers at the bend in the loop and thereby cause the same to stand out as a pile.
3. The method of producing a knitted pile fabric which includes supporting a loop of the thread of the fabric while effecting enchaining operations and straining the loop over the support beyond the tensile strength of its fibers to break the fibers and cause them to stand out as the pile.
4. The method of producing a knitted pile fabric which includes looping a thread of the fabric over a support and separating a portion only of the fibers of the thread at the bend of the loop to thereby provide a loop carrying outstanding pile.

5. The method of producing a knitted pile fabric which comprises supporting a thread of the fabric in looped formation and separating a part only of the fibers at the bend of the loop while effecting the enchaining operation.

6. The method of producing a knitted fabric which includes supporting two threads in separated looped formation and partially rupturing one of the loops at the bend therein while effecting the enchaining operation.

7. The method of producing a knitted pile fabric which includes supporting two threads of the fabric at different levels and pulling both down to substantially the same level and thereby applying sufficient tension to the thread of the higher level to break part only of the fibers of which the same is composed.

8. The method of producing a knitted pile fabric which includes the placing of the thread under an abnormal tension to cause a rupture of certain fibers therein when the loop is formed while effecting the enchaining operation.

In testimony whereof I affix my signature.

LOUIS ALBERT O'LENA.
